UNITED STATES PATENT OFFICE

152,768

DESIGN FOR A PORTABLE IRONING
MACHINE

Allan L. Briggs, Jamestown, N. Y., assignor to
Blackstone Corporation, Jamestown, N. Y., a
corporation of New York

Application August 16, 1948, Serial No. 148,130

Term of patent 14 years

(Cl. D49—1)

To all whom it may concern:

Be it known that I, Allan L. Briggs, a citizen of the United States, residing at Jamestown, in the county of Chautauqua and State of New York, have invented a new, original, and ornamental Design for a Portable Ironing Machine, of which the following is a specification, reference being had to the accompanying drawing, forming part thereof, and in which:

Fig. 1 is a front elevational view of a portable ironing machine showing my new design;

Fig. 2 is a top plan view;

Fig. 3 is a view of the control end of the machine;

Fig. 4 is a rear elevational view; and

Fig. 5 is a view of the other end of the machine.

I claim:

The ornamental design for a portable ironing machine, substantially as shown.

ALLAN L. BRIGGS.
